Attorney

Thomas Bilyeu

UNITED STATES PATENT OFFICE

WILLIAM A. WYNKOOP, OF PORTLAND, OREGON

VENTILATING JOIST POCKET

Application filed August 6, 1928. Serial No. 297,869.

The primary purpose and object of my invention is for use in combination with masonry and concrete walls and wherein wooden and other structural joists, girders and other structural members are used in combination with said walls to form supporting pockets and the like for such structural wooden members.

Heretofore where wooden members have been used in such construction the end of the wooden member resting in and upon said walls rapidly deteriorates due to a wet and dry condition or moist condition prevailing within the wall which is transferred to the wooden member thus permitting a fungus development within the wooden member, as dry rot.

In my new and improved device, the pocket into which the wooden member is made to engage is ventilated due to the tapering walls and further due to corrugations disposed within the wall members thereby permitting a circulation of air in and around the supporting end of the structural member.

A further object of my new and improved construction resides in a pocket forming member having uniform upwardly tapering side walls made of corrugated material and that may be nested in shipment from the point of origin thereby lessening the possibility of damage of the device and at the same time lessening the transportation, handling and other freight charges.

And still further objects of my new improved pocket forming member resides in supporting holes being formed within the device; and holes being formed in the rear walls thereof through which fastening elements may be passed to engage upon the wood members to maintain the same in relatively fixed position to that of the pocket formed.

With these and incidental objects in view, the invention consists in certain novel features of construction and combination of parts, the essential elements of which are set forth in the appended claims, and a preferred form of embodiment of which is hereinafter shown with reference to the

drawings which accompany and form a part of this specification.

In the drawings:

Fig. 1 is a perspective, front view of the assembled pocket forming member.

Fig. 2 is a vertical, sectional view, taken on line 2-2 of Fig. 1, looking in the direction indicated.

Fig. 3 is a side view of a masonry wall, showing one of my new and improved devices in place therein. Further showing a structural wooden beam in place therein with the fastening therefor.

Fig. 4 is a cross section view, taken on line 4-4 of Fig. 1, looking in the direction indicated.

Fig. 5 is a perspective bottom end view of two of my pocket forming members shown in position to be nested for shipment.

Like reference characters refer to like parts throughout the several views.

1 is the masonry wall into which the pocket is to be formed which may be made of brick or concrete or other masonry construction in combination with which supporting beams and girders of wood or other material are to be supported. My pocket forming member in preferred embodiment consists of a rear wall 1A and side walls 2 and 3, and a bottom wall 4. A flange 5 is disposed around the peripheral edge of the side walls and the top of the back through which holes 6 are made the object and purpose of which is to permit of the passing of fasteners therethrough for maintaining the pocket forming element fixed relative to that of the masonry wall 1. Corrugations 7 are formed within the bottom, sides and rear walls of the device to facilitate ventilation about the supported end of the structural member 8. The side walls are made inwardly sloping to leave air spaces 9 and 10 at either side of the structural member and the corrugations formed within the walls give added rigidity and strength to the pocket forming member and at the same time facilitates circulation of air around the end of the structural member. Holes 11 and 12 are disposed in the back of the pocket forming

member to permit of the passing of the fastening 13 therethrough to maintain the structural beam 8 fixed relative to that of the masonry wall 1. The fastenings 13 are secured to the wall by any suitable fastening means, as by an anchor 14. The base or bottom of the pocket forming device is preferably made, as illustrated in Fig. 2, wherein a flap 15 is disposed inwardly from the rear wall 1A; flaps 16 and 17 formed from the side walls are formed inwardly and contact with the flap 15. An opening is formed in the flap 15 and in the flap 17, through which a tongue 18 formed from the flap 16 is upwardly extended and bent over, as illustrated at 19, thereby forming a locking connection between the elements forming the bottom of the pocket forming device, thus affording rigidity to the assembly.

20 While the form of mechanism herein shown and described, is admirably adapted to fulfill the objects primarily stated, it is to be understood that it is not intended to confine the invention to the one form of embodiment herein shown and described, as it is susceptible of embodiment in various forms all coming within the scope of the claims which follow:

What I claim is:—

- 30 1. A joist pocket comprising a rearwardly inclined corrugated rear wall having holes formed therein for the passing of fastening members therethrough, corrugated side walls inwardly sloping and being an integral part of the rear wall element, a flange disposed about the peripheral front edges of the side and rear walls, and a base formed from the flap extensions of the rear and side walls, substantially as shown and described.
- 40 2. An article of manufacture comprising a beam pocket made from one piece of sheet metal having a rearwardly inclined back wall, inwardly inclined side walls, and a bottom formed from the free ends of the back and side walls, a flange disposed about the outer edge of the pocket, and a plurality of minutely spaced parallel grooves disposed about the pocket walls for permitting the entrance of air about most all the parts 50 of the beam disposed within the pocket, substantially as shown and described.

WILLIAM A. WYNKOOP.
